UNITED STATES PATENT OFFICE.

WILLIAM W. DEAN, OF ELYRIA, OHIO, ASSIGNOR TO THE DEAN ELECTRIC COMPANY,
OF ELYRIA, OHIO, A CORPORATION OF OHIO.

TELEPHONE.

1,036,805.

Specification of Letters Patent. Patented Aug. 27, 1912.

Application filed August 9, 1909. Serial No. 511,982.

To all whom it may concern:

Be it known that I, WILLIAM W. DEAN, a citizen of the United States, residing at Elyria, in the county of Lorain and State 5 of Ohio, have invented certain new and useful Improvements in Telephones; and I do hereby declare the following to be a full, clear, and exact description of the invention, such as will enable others skilled in the 10 art to which it appertains to make and use the same.

This invention relates to magnetic telephones and more particularly to telephone receivers, but the utility thereof is not limited 15 to such a purpose, as among other uses I may apply it as a transmitter.

I have produced an improved receiver by providing a magnetic circuit of very low reluctance and one acting on the receiver 20 diaphragm in such a way that I am able to employ an electromagnet coil of low resistance. To accomplish this, I have provided a plurality of U-shaped soft iron wires arranged so one of the limbs of each wire 25 forms an element of the periphery of a cup shaped receptacle, while the other limb projects upward from the bottom of the receptacle forming an element of the magnet core. I also endeavor to distribute the attraction 30 between the magnet and the diaphragm over the surface of the whole and to make the same more uniform than with the telephone receivers now in use. To accomplish this, I may arrange the exterior ends of the flux 35 conductors in a continuous circuit around the exterior of the magnet as illustrated in the drawing. I also endeavor to provide a device of this character, which may be cheaply and easily constructed, and to this 40 end I set the magnet coil within the cup and over the core. The whole is then placed within a second cup and the interstices among the various parts filled with a liquid insulating material, which solidifies, insulating 45 the various parts from one another. While I have thus described my purposes and briefly the mode of realizing them, I do not desire to be limited thereby.

My invention will be best understood by 50 referring to the following description when taken in connection with the accompanying drawings, showing one specific embodiment thereof, while the scope may be more particularly pointed out in the appended claims.

Figure 1 is a cross section of my im-

proved telephone receiver showing the various parts. Fig. 2 is an end elevation of the receiver cup with the diaphragm removed.

Referring to the drawings and embodiment of my invention there shown, I have illustrated a fragment of a receiver shell 1 with the ear piece 2 screwed thereon. Within this shell I inclose a receiver cup 3. The bottom forms a base piece at the ear end 60 of the cup and the ring 4 screws on clamping the diaphragm 5 between this and the cup. An insulated piece 6 is attached to the outside of the bottom of the cup and carries the terminals 7 and 8. The terminals 70 of the electro-magnet are shown connected at 9 and 10 to the terminals 8 and 7. A cup 11 is fastened to the bottom of the receiver cup and on the inside thereof. A plurality of elements 12 of soft iron, or 75 other high flux conducting material, are doubled over and assembled in such a way that the outside ends form a cup shaped receptacle while the inside elements, or limbs project upward at the center forming a core 80 for an electro-magnet. The periphery of the cup is shown at 14 and may be formed of several layers of these flux conductors. An electromagnet coil 15 is then placed over 85 the core and within the receptacle, and these terminals connected to 7 and 8 as previously described. The spool head is shown at 16, a layer of rigid material 17 on top of the head 16 and between the projecting ends of the flux conducting elements. Screw 20 90 projects through the bottom of the receiver cup into the bottom of the second cup attaching the same thereto.

In producing my apparatus, I proceed by 95 the following method: The wires, or flux conductors are doubled over and arranged as described into a cup shaped member with the core projecting from the center. The electromagnet coil is placed over the core 100 and within the cup and the whole inserted into another cup. A liquid insulating material is then poured over the whole until the interstices are filled and a layer is accumulated on top of the spool head up to the rim 105 of the outside cup. When this solidifies it furnishes a backing for the wires, which may be then trimmed off even with the rim of the cup and the layer of solidified insulating material. The interstices between the flux conductors are thus filled with an insu- 110

lating material which thoroughly insulates them one from another and prevents the flow of any eddy currents in the magnetic circuit. The spaces between the wires are filled in, increasing the insulation there between and the whole is rendered compact and solid. I thus produce a highly efficient receiver which attracts the diaphragm at the center and at points equally distant therefrom on the periphery of a circle. This prevents any buckling or tendency of the bottom to sag along a line, as sometimes occurs with receivers which are controlled by a horse-shoe shaped magnet. The device is also easily manufactured as will be clear to those skilled in the art from the description of the method of manufacturing the same.

While I have shown the telephone in this particular preferred embodiment, it will be obvious to those skilled in the art that numerous and extensive departures from the forms and detail of the apparatus here shown, may be made without departing from the spirit of this invention, the same being herein shown solely for the purpose of clearly illustrating one specific embodiment thereof.

I claim:

1. In a telephone receiver, the combination of a base, a cup supported on said base, a magnet spool within said cup, a magnet coil wound thereon, circuit connections for said coil, a diaphragm supported in proximity to said magnet, said diaphragm free to vibrate in response to said magnet, a plurality of soft iron flux conductors forming the core of said magnet coil, said flux conductors being insulated from one another, a

return flux circuit of said magnet coil, the ends of said conductors extending beyond the magnet coil at both ends and a layer of solid material over the magnet spool and between the ends of the flux conductors, the ends of the flux conductors extending to the top of said layer of solid material. 45

2. In a telephone receiver, the combination of a receiver shell, a base mounted in said shell, a cup removably fastened to said base, a plurality of magnetic metal flux conductors bent into U-shapes in said cup, one limb of each flux conductor being in proximity to the edge of the cup and forming an element of a cup like receptacle formed by said limb, the other limb of each flux conductor projecting upward at the center and all forming the core of an electro-magnet, a magnet spool mounted over the limbs at the center and inside the limbs at the sides, a coil on said spool, terminals for said coil conductors leading to said terminals, the ends of the flux conductors extending beyond the end of the spool, insulating material poured between the flux conductors, a layer of insulating material on top of said spool and between the projecting ends of the flux conductors, the ends of the flux conductors projecting to the top of said layer, a vibratile diaphragm adapted to be actuated by said magnet and means to clamp the edges of said diaphragm to said base. 70 65

In testimony whereof I affix my signature in presence of two witnesses.

WILLIAM W. DEAN.
